[57] CLAIM

The ornamental design of a skid steer loader, as shown and described.

DESCRIPTION

FIG. 1 is an isometric view of a skid steer loader incorporating our new design;

FIG. 2 is a left side elevation view thereof, the right side elevation view being a mirror image;

FIG. 3 is a top plan view thereof;

FIG. 4 is a front elevation view thereof; and,

FIG. 5 is a rear elevation view thereof.

The broken line showing is for illustrative purposes only, and forms no part of the claimed design.
